UNITED STATES PATENT OFFICE.

CASPAR BLUMER, OF GUTTENBURG, NEW JERSEY.

CIGAR-PERFORATOR.

SPECIFICATION forming part of Letters Patent No. 781,488, dated January 31, 1905.

Application filed September 8, 1904. Serial No. 223,680.

To all whom it may concern:

Be it known that I, CASPAR BLUMER, a citizen of the Republic of Switzerland, and a resident of Guttenburg, in the county of Hudson 5 and State of New Jersey, have invented a new and Improved Cigar-Perforator, of which the following is a full, clear, and exact description.

The object of the invention is to provide a new and improved cigar-perforator more especially designed for penetrating the sides of the cigar at or near the point thereof to provide draft-holes for drawing the smoke through, the arrangement being such that the 15 wrapper is not loosened or unraveled when forming the draft-holes by the instrument.

The invention consists of novel features and parts and combinations of the same, as will be more fully described hereinafter, and then 20 pointed out in the claims.

A practical embodiment of the invention is represented in the accompanying drawings, forming a part of this specification, in which similar characters of reference indicate corresponding parts in all the views.

Figure 1 is a perspective view of the improvement as applied. Fig. 2 is an enlarged side elevation of the improvement, and Fig. 3 is a plan view of the same.

The cigar-perforator is preferably made from a single piece of spring metal, bent to form a U-shaped spring A, terminating at its ends in cup-shaped members A' for receiving the pointed end of a cigar B, as plainly illustrated in Fig. 1, the said cup-shaped members being capable of yielding for cigars of different thicknesses. From the sides of the cup members of the spring are struck-up 35 spring-arms A², terminating at their free ends in teeth A³, standing at angles to the spring-arms and approximately in a plane extending through the axis of the cup-shaped members A'. Normally the teeth A³ are somewhat above the outer faces of the cup-shaped members A', so that the tapering or pointed end 45 of the cigar can be readily placed in position in the cup-shaped members A', as illustrated in Fig. 1, and then the operator on pressing on the free ends of the spring-arms A² causes 50 the teeth or points A³ to penetrate the wrap-

per and a portion of the filler of the cigar to provide draft-holes therein. It is understood that as soon as the operator releases the pressure on the spring-arms A² the latter return outwardly to their normal positions, thus disengaging the cigar to permit of removing the perforator from the cigar. The cigar is now pierced with a number of holes on opposite sides, at or near the point thereof, so that the cigar when lighted and used by the smoker 60 is provided with suitable draft-holes for drawing the smoke through.

By the arrangement described the terminal of the cigar need not be cut off, and consequently the wrapper is not liable to become 65 loose or unraveled, and at the same time the nicotine contained in the tobacco is not liable to pass out of the draft-holes, but accumulates in the tobacco forming the extreme point or terminal of the cigar.

The perforator is very simple and durable in construction and can be cheaply manufactured.

Having thus described my invention, I claim as new and desire to secure by Letters Patent— 75

1. A cigar-perforator constructed of a single piece of spring metal, and comprising a U-shaped member provided at the ends thereof with receiving members for the end of a cigar, said member having spring-arms struck up 80 therefrom and provided at their free ends with perforating devices.

2. A cigar-perforator comprising a cup-shaped receiver formed with openings in its walls, and struck-up spring-arms integral on 85 the receiver and arranged on opposite sides thereof, the spring-arms being provided with teeth for penetrating the cigar at the sides thereof.

3. A cigar-perforator made of a single piece 90 of metal and consisting of a receiver for the end of a cigar, and struck-up spring-arms having teeth for penetrating the sides of the cigar, between the ends of the said receiver.

4. A cigar-perforator comprising a receiver 95 for the end of the cigar and consisting of a U-shaped spring provided at its ends with receiving members, and spring-arms integral with the said spring and provided at their free ends with teeth.

5. A cigar-perforator made of a single piece of metal and comprising a **U**-shaped spring terminating at its free ends in cup members, and spring-arms integral with the said spring and provided at their free ends with teeth, for penetrating the sides of the cigar.

6. A cigar-perforator constructed of a single piece of metal, and comprising a **U**-shaped member provided at the ends thereof with receiving members for the end of a cigar, said member having spring-arms struck up there-

from and provided at their free ends with perforating devices, the latter normally occupying a position beyond the inner surfaces of said receiving members.

In testimony whereof I have signed my name to this specification in the presence of two subscribing witnesses.

CASPAR BLUMER.
